UNITED STATES PATENT OFFICE.

CHESTER H. THORDARSON, OF CHICAGO, ILLINOIS.

METHOD OF MAKING INSULATING ELEMENTS.

1,329,815.

Specification of Letters Patent.

Patented Feb. 3, 1920.

Application filed March 20, 1915. Serial No. 15,929.

To all whom it may concern:

Be it known that I, CHESTER H. THORDARSON, a citizen of the United States, and a resident of Chicago, in the county of Cook and State of Illinois, have invented certain new and useful Improvements in Methods of Making Insulating Elements; and I do hereby declare that the following is a full, clear, and exact description thereof, reference being had to the accompanying drawings, and to the characters of reference marked thereon, which form a part of this specification.

This invention relates to a novel method of making insulating elements composed of a plurality of superposed turns or sheets of insulating material which are impregnated with a flowable insulating medium during the winding or laying on operation. Said insulating element may have the form of a tube to surround the magnetic circuit of an electro-magnetic device, as a transformer, or may be of flat form for general insulating uses. The method herein described is an improvement on the method disclosed in my prior United States Letters Patent Number 1,220,377, dated March 27, 1917, and the improvements relate principally to means for driving out or expelling the air and water from the sheet material and the insulating medium so as to produce a dry and hard resultant product of uniform resistance throughout to the passage of an electric current.

The improvement in the method of making such insulating elements consists, in part, in winding a sheet of suitable fibrous insulating material, as paper, into a tube in the presence of a high vacuum, the sheet of material being impregnated with a fluid insulating medium which subsequently hardens and which constitutes also a thin film between contiguous convolutions of the rolled sheet. The high vacuum has the effect of drawing the air and gases from the body of the sheet material and from the insulating compound, which avoids the formation of bubbles in the walls of the tubes, thereby increasing the density and hardness of the resultant product.

As an additional means for driving the moisture and other foreign matter from the insulating sheet prior to the winding operation, I may subject said sheet just before it is wound into the tube to the influence of an electro-static field produced between an

elongated electrode included in a high potential circuit and a similar electrode included in a portion of the machine which is grounded. Conveniently one of the electrodes may consist of a metal roller about which the sheet is guided to the forming tube between the insulating bath and the forming tube.

When the insulating element assumes the form of a flat sheet it may be made by slitting or dividing the tube thus formed before the insulating compound has hardened, and thereafter flattening the tube or sheet and applying pressure to press the layers together when the insulating compound hardens.

In the drawings:

Figure 1 is a horizontal sectional view of a convenient form of machine for practising my novel method.

Fig. 2 is a transverse section thereof.

Fig. 3 is an enlarged detail of the laying on or ironing roller and the electro-static electrodes.

Fig. 4 is a diagrammatic perspective of the essential parts of the tube forming mechanism, and also the circuit wiring to be hereinafter described.

Figs. 5 and 6 are diagrammatic illustrations of slight variations of the method.

Fig. 7 is a diagrammatic view showing a method of producing a flat form of insulating element.

The tube winding mechanism is a power driven self contained machine which is located within an air tight tank 10 which has connections through a suitable hose or pipe 11 with a vacuum pump 12 or other source of low pressure whereby a high vacuum is maintained in the tank. As nearly a complete vacuum as is practicable is desired. The tube winding mechanism comprises a fixed frame, consisting of rigidly connected upright and horizontal members 14, 15, respectively, of any suitable design, which is provided with wheels or rollers 16 which travel on tracks 17, 17 within the lower part of the tank 10. Said tank 10 is preferably circular in cross section and is provided at one end with a fixed wall 18 and at its other end with a removable wall 19. When said movable wall 19 is removed said winding mechanism may be run outwardly from said tank onto an extension track 20, indicated in Fig. 1, arranged in line with the tank rails 17 so that free access may be had to the

winding mechanism to remove a wound tube therefrom or to replace the paper or other sheet roll thereon from which the tube is wound.

5 The tube may be wound upon any suitable mandrel 25 which may be made like the collapsible mandrel shown in my aforesaid prior patent, the shaft 26 of said mandrel being mounted in bearings 27 supported on 10 the winding mechanism frame. 28 designates a rotative reel mounted in said frame which receives a roll of sheet material that is unwound therefrom to produce the insulating tube. The sheet α is carried from the 15 reel over a guide roller 29 rotatively mounted at the top of the frame, thence downwardly into a receptacle 30 which contains the insulating compound in liquid state, being guided by rollers 31, 32 within said receptacle. The sheet is continued from the 20 roller 32 over a roller 35 which, in the present instance, is a metal roller and constitutes one of the electrodes of a high tension circuit, and from said roller 35 the sheet is 25 wound upon the mandrel 25 or the forming tube. The bearings for the roller 35 are carried by the upper ends of insulators 35'. At the line at which the sheet is laid on said mandrel or the forming tube there is provided 30 an ironing or pressing roller 36 which presses the sheet closely upon the forming tube in a manner similar to the like ironing roller shown in my aforesaid prior application. The mandrel 25 may be rotated by an electric 35 motor 38 through the medium of a worm and worm wheel drive 39. A suitable tension device may be applied to the roll supporting reel or to the roll itself to prevent a too free unwinding of the sheet material 40 from the roll. One form of tension device suitable for the purpose is shown in my aforesaid prior patent.

The ironing roller 36 is mounted in the upper ends of swinging arms 42, one at each 45 end of the machine, and which are pivoted at their lower ends to the frame and swing at their upper ends toward and from the mandrel. The said roller 36 is pressed toward the forming tube by a spring pressure, which 50 may be effected by means of springs 44 each attached at one end to the swinging levers 42 and connected at their other ends by links 45 to hand levers 46 which are pivoted at their lower ends to the frame and are adapted 55 to be locked at their upper ends to suitable racks 47. The hand levers 46 provide means whereby the spring pressure of the roller 36 against the forming tube may be varied.

60 Between the rollers 32 and 35 the sheet is subjected to a scraping operation for the purpose of removing surplus insulating material therefrom. Such scraping operation is herein shown as effected by means of the 65 sharpened edges of upper and lower scraper

bars 48, 49, respectively, which are attached at their ends to and extend between the swinging roller bearing arms 42. The said scraper bars, as herein shown, have the form of angle bars and one edge of each bar is 70 sharpened to constitute a scraping edge. As herein shown, the vertical member of the lower bar is sharpened at its lower edge and the sheet passes upwardly thereacross and along the flat face of the bar to scrape the 75 excess material from the outer face of the sheet, and the inner face of the sheet is brought to bear against a sharpened scraping edge formed on the horizontal member of the upper bar 48.

80 Preferably the guide roller 32 and the scraper bars 48, 49 are provided with suitable relatively low resistance heating elements, 50, 52, 51, respectively, which are connected with a suitable source of relatively 85 low pressure current so that said roller and bars may be kept suitably heated so as to prevent the congealing of the liquid insulating medium on the surface of the sheet before it is scraped therefrom as it emerges 90 from the insulating bath. Said resistance or heating elements of the scraper bars and roller are shown as connected in multiple to a supply line at the plug 55 and the feed side of the circuit is provided with a switch 95 56 by which current to the heating elements is controlled. The insulating medium in the tank may be maintained in a fluid state by any suitable application of heat as, for instance, by the use of burner pipes 57. Preferably also the tank may be provided with one or more internal heating elements 58, one being herein shown as located near the rising side of the sheet α to assist in maintaining the insulating medium in a suitably 100 fluid condition for application to the sheet. These heating elements need be only of comparatively low heating power. The heating elements of the scraper bars may be insulated from the bars by being wrapped in 110 covers of a suitable insulating material, as asbestos. They prevent the scraper bars from chilling the coating on the paper so that, thereby the said insulating medium may be kept sufficiently fluid to be readily 115 removed or scraped therefrom. The resistance or heating element 58 is also inclosed in an insulating cover and it is connected also to the plug 55 and is provided with an independent switch 59 whereby the control 120 of the current to the said heating element 58 may be independent of the control of the current to the scraper bar and roller heating elements.

125 The motor 38 is fed from a supply plug 60, and the motor circuit is provided with the usual regulator 61 and with a cut-out switch 62. To the feed side of the motor circuit is connected a series of lamps 64 which are shown in Fig. 2 as supported 130

in any suitable manner on the tank 10, the return side of the lamp circuit being provided with a switch 65.

Arranged between the laying on or ironing roller 36 and the lower scraper bar 49 is a shearing device for cutting the sheet which is being wound after the desired number of turns have been wound into the tube. The shearing device herein diagrammatically shown consists of a fixed blade 67 and a swinging blade 68, both supported in any suitable manner on the swing bars 42. Normally the blades are separated, as indicated in Figs. 3 and 4, and the paper after its emergence from the insulating bath passes upwardly between the shearing blades. The swinging blade is held in its open position by means of a latch 69 which is provided with a tooth to engage a pin 70 on the said swinging blade. The latch is provided at one end with an armature 71 which co-acts with the core of a tripping coil 72, one side of the energizing circuit of which, as herein shown, is connected to the feed side of the motor circuit, the other side being connected to the return side of the said motor circuit. The said tripping coil circuit is provided with a switch 73 which, when closed, completes the circuit through the coil and energizes the same to trip the latch 69 and permit the swinging blade to be moved toward the fixed blade under the influence of a shearing spring 75, to thereby sever the sheet.

After the sheet has been severed by the shearing device the end wall 19 of the tank 10 is removed and the winding and sheet insulating mechanism is drawn outwardly onto external tracks 20 which are fitted in end to end relation to the tank tracks 17. The connection of the various circuit wires to the internal terminals is such as to permit the mechanism to be thus drawn outwardly from the casing 10 without disconnecting the circuit.

In order to prevent air leaking into the spaces between the convolutions or turns of the wound tube at the ends thereof after its withdrawal from the tank or casing 10, the rotation of the finished tube is continued while it is subjected to the drying influence of a fan or other suitable drying means. The application of heat is continued to the insulating medium to maintain it in a liquid state. Thus the liquid insulating medium seals the interspaces between the convolutions or turns of the tube and prevents leakage of air therebetween.

After the tube has been sufficiently cooled the winding mandrel and the said tube are removed from the frame, and the winding mandrel removed from the tube. The tube may, if desired, be subjected to an exterior pressure in the manner indicated in my aforesaid patent to prevent the separation

of the turns or convolutions during the further setting or hardening of the tube. It will be understood, of course, that the tube may be wound on a cylindric mandrel in which event the exterior pressure will not usually be applied during the setting or hardening of the tube. As before stated if the final insulating element is to be flat, the tube is removed from the mandrel prior to the setting or hardening operation and is split and flattened and subjected to pressure while being dried or set.

The roller or electrode 35 is connected to a source of high tension pulsating direct current through the means of a conductor 77, said conductor being insulated from the tank 10 by a suitable insulator 78. The conductor 77 is attached to one end of the metal roller or electrode 35 and the circuit is open at the other end of the electrode. The upper ends of the swinging arms 42 are turned inwardly and downwardly to pass over the upper edges of the end walls of the insulating bath receptacle, the ironing roller 36 being rotatively mounted on the downwardly turned ends of said swinging arms within the receptacle. One or both of the scraper bars, or other metal part of the frame, is grounded so that there is set up between the said electrode or roller 35 and the said grounded metallic portion of the frame an electrostatic discharge which has the effect of driving the moisture from the sheet that has just passed between the scraper bars. In this manner the sheet, while being thoroughly impregnated with the insulating medium, is free from varying thicknesses of the insulating medium between the layers or convolutions thereof, and the resultant tube is also free from globules of water and air both in the body of the sheet and between the convolutions or layers thereof. Thus the tube produced possesses uniform insulating qualities throughout its area to a maximum degree.

After the tube and the mandrel have been removed from the frame, another mandrel or the same mandrel is applied thereto, another roll of paper is applied to the reel 28 and is attached at its leading edge to the mandrel, and thereafter the mechanism thus equipped is pushed into the casing or tank and the end wall 19 is fastened thereto, whereupon the operation of winding a new tube is begun.

Preferably the tank is provided with one or a number of windows 80 through which the tube winding operation may be observed from the exterior of the tank.

In some cases I find it advantageous to subject the sheet of insulating material to a second treatment of the insulating compound and at a temperature lower than the initial treatment. This has been found to be advantageous for the reason that in order

to perfectly impregnate the insulating sheet with an insulating compound, such for instance as paraffin, it is necessary to heat the compound to a substantially high temperature, in the neighborhood of 300 degrees Fahrenheit. It has been found in some cases that this temperature produces a vapor which tends to cling in a thin film to the surface of the sheet and such films of vapor, even though they be very thin, are such that in the completed tube the structure is more or less loose and not so dense as is necessitated by the insulating requirements. In order to overcome this defect, where found, I may subject the initially treated sheet to a second treatment in an insulating compound bath under a lower temperature than the initial bath as, for instance, in the neighborhood of 180 to 200 degrees Fahrenheit when winding the final tube. When this practice is followed the initially treated sheet may be wound on a roll or mandrel in the high temperature bath in the same machine or apparatus in which the final tube is wound and the sheet is thereafter unrolled from the initial tube before the insulating compound has set or hardened and passed through the lower temperature bath and wound into the final tube on the mandrel, as shown in Fig. 5.

The same result may be secured by thus passing the sheet successively through an initial high temperature bath and a second lower temperature bath without winding the sheet between said baths, as shown in Fig. 6, but permitting the sheet to pass directly from the high temperature to the low temperature bath and cooling it in transit therebetween, if found necessary.

When it is desired to produce a flat sheet, the tube may be slit longitudinally as indicated at small *b* in Fig. 7 and is spread flat to produce the sheet *C*. The sheet is compressed during the time the insulating compound is cooling between upper and lower members 94, 95 by any suitable pressing device indicated by the arrow points in Fig. 7. The tapered edges of the sheet produced by flattening the slitted tube may be thereafter sheared off on the dotted lines indicated at *c'* to produce squared edges.

It will be understood that the mechanism herein shown for practising my novel method of producing insulating elements is merely one example of a number which may be employed, and it is furthermore understood that the illustration of said mechanism is largely diagrammatic in its nature.

I claim as my invention:—

1. The method of making insulating elements which consists in assembling a sheet of insulating material into a laminated element, passing the sheet through and impregnating the same immediately at the assembling operation with a heated bath of liquid

insulating compound which hardens as it cools, thereafter allowing the product to cool, and applying pressure symmetrically to opposite sides of the element to press the superposed layers together during the cooling of the insulating compound. 70

2. The method of making insulating elements which consists in winding a sheet of insulating material upon a form partially submerged in a heated bath of insulating compound which hardens when cooled, and thereafter allowing the resultant product to cool. 75

3. The method of making insulating elements which consists in winding a sheet of insulating material upon a collapsible form partly submerged in a heated insulating medium, allowing the product to cool while under pressure to press the layers together and thereafter collapsing and removing the form. 80

4. The method of making insulating elements which consists in winding a sheet of insulating material upon a form partly submerged in a heated insulating compound and thereafter allowing the product to cool under pressure greater than under which it was wound. 90

5. The method of forming an insulating element which consists in rolling a sheet of insulating material into a tube against a tension exerted on the sheet while the tube is partially submerged in a melted insulating compound and afterward allowing the resultant product to cool. 95

6. The method of making insulating elements which consists in impregnating a sheet with insulation, winding the sheet material upon a form immediately adjacent to its reception of insulation, excluding air and water from the sheet immediately adjacent to the line on which it passes upon the form, and thereafter removing the form. 100

7. The method of making insulating elements which consists in passing a sheet through an insulating bath, winding the sheet upon a form which rotates partially submerged in said bath, excluding air and water from the sheet immediately adjacent to the line on which it passes upon the form, thereafter allowing the resultant shell to cool while under pressure greater than that under which it was formed, and thereafter removing the form. 110

8. The method of forming an insulating element which consists in rolling a sheet of insulating material into a tube in the presence of a melted insulating compound, afterward longitudinally slitting the tube and spreading it flat and allowing the flattened body to cool under pressure. 120

9. The method of making insulating elements which consists in winding a sheet of insulating material to produce a hollow roll in the presence of a heated bath of insulat- 130

ing compound which hardens when cooled, whereby the sheet becomes impregnated with the insulating medium, longitudinally slitting the hollow roll and flattening the 5 same and thereafter allowing the product to cool when subjected to pressure to force the layers together.

10. The method of making an insulating element which consists of assembling upon 10 each other layers of an insulating material impregnated with an insulating compound, and subjecting all parts of the layer to the influence of a high, continuous vacuum before impregnation, and thereafter allowing 15 the product to harden.

11. The method of making an insulating element which consists in winding a sheet of insulating material into a roll in a continuous vacuum, impregnating the sheet before winding with an insulating compound 20 and thereafter allowing the product to harden.

12. The method of making an insulating element which consists in winding a sheet 25 of insulating material into a roll in a continuous vacuum, impregnating the sheet before winding with an insulating compound, scraping the surplus of insulating material from the sheet before winding and thereafter allowing the product to cool.

13. The method of making an insulating element which consists in superimposing upon each other layers of insulating material 35 impregnated with an insulating compound in the presence of a high vacuum, subjecting the sheet to the action of an electro-static discharge and thereafter allowing the product to harden.

14. The method of making an insulating element which consists in superimposing 40 upon each other the layers of insulating material impregnated with an insulating compound and subjecting the sheet to an electro-static discharge.

45. The method of making an insulating element which consists in winding a sheet of insulating material into a tube on a rotating member in a heated bath of insulating material, thereafter cutting the sheet, thereafter cooling the formed tube and at the same time continuing the rotation of the tube in the bath to prevent the entrance of air between the overlying layers at the end of the resultant product.

55. The method of making an insulating element which consists in winding in a high vacuum a sheet of insulating material into a tube in a heated bath of insulating material, thereafter releasing the vacuum and thereafter continuing the rotation of the tube in the bath while cooling the tube.

60. The method of forming an insulating element which consists in rolling a sheet of insulating material into a tube in the presence of a liquid insulating compound under

a forming pressure which effects a tight winding of the sheet and in the presence of a continuous vacuum and thereafter allowing the compound to harden under atmospheric pressure.

70

18. The method of forming an insulating element which consists in rolling a sheet of insulating material into a tube in a melted insulating compound under a forming pressure which effects a tight winding of the 75 sheet and in the presence of a vacuum, thereafter releasing the vacuum while continuing the rotation of the tube in the insulating compound under the forming pressure.

19. The method of forming an insulating element which consists in rolling a sheet of insulating material into a tube in a melted insulating compound under a forming pressure which effects a tight winding of the sheet and in the presence of a 80 vacuum, thereafter releasing the vacuum while continuing the rotation of the tube in the insulating compound under the forming pressure and subjecting the sheet to the action of an electro-static discharge preliminary to its winding operation.

20. The method of making an insulating element which consists in winding a sheet 85 of insulating material into a roll in the presence of a heated bath of insulating compound to impregnate said sheet and thereafter rewinding said impregnated sheet into a tube.

21. The method of making an insulating element which consists in winding a sheet 90 of insulating material into a roll in the presence of a heated bath of insulating compound to impregnate said sheet and thereafter rewinding said impregnated sheet into a tube in the presence of a 95 vacuum.

22. The method of making an insulating element which consists in winding a sheet 100 of insulating material into a roll in the presence of a heated bath of insulating compound to impregnate said sheet and thereafter rewinding said sheet into a tube and subjecting said sheet as it is wound upon the tube to the influence of an electro-static discharge.

110

23. The method of making an insulating element which consists of winding a sheet 115 of insulating material into a roll in the presence of a heated bath of insulating compound to impregnate said sheet and thereafter rewinding said impregnated sheet into a tube in the presence of a heated bath of insulating material of less temperature than the original bath.

24. The method of making insulating 120 elements which consists in subjecting a sheet of insulating material successively to two baths of insulating compound of progressively decreasing temperatures to impregnate the sheet, thereafter forming the 125

130

sheet thus impregnated into a laminated insulating element, and thereafter allowing the insulating element to set or harden.

25. The method of making insulating elements which consists in subjecting a sheet of insulating material successively to two baths of insulating compound of different temperatures to impregnate the sheet, thereafter forming the sheet thus impregnated into a laminated insulating element in the presence of a vacuum, and thereafter allowing the insulating element to set or harden.

26. The method of making insulating elements which consists in subjecting a sheet of insulating material successively to two baths of insulating compound of progressively decreasing temperatures to impregnate the sheet, thereafter forming the sheet thus impregnated into a laminated insulating element in the presence of a vacuum, thereafter releasing the vacuum, and thereafter allowing the insulating element to set or harden in the presence of said bath.

27. The method of making an insulating

element which consists in assembling upon each other successive layers of an insulating material, impregnating the material with an insulating compound prior to the assembling of the layers and subjecting the material prior to its impregnation to a continuous vacuum during the assembling operation.

28. The method of making an insulating element which consists in assembling upon each other successive layers of an insulating material, impregnating the material with an insulating compound prior to the assembling of the layers and subjecting both the formed element and the insulating material prior to its impregnation to a continuous vacuum during the assembling operation.

In testimony, that I claim the foregoing as my invention I affix my signature in the presence of two witnesses, this 26th day of February, A. D. 1915.

CHESTER H. THORDARSON.
